UNITED STATES PATENT OFFICE.

LAWRENCE E. JOHNSON, OF WINTHROP, MASSACHUSETTS, ASSIGNOR TO VICTOR SHOE MACHINERY CO., OF BOSTON, MASSACHUSETTS, A CORPORATION OF MASSACHUSETTS.

SOLE-LEATHER-CUTTING MACHINE.

1,137,213.

Specification of Letters Patent. Patented Apr. 27, 1915.

Application filed April 6, 1914. Serial No. 830,078.

To all whom it may concern:

Be it known that I, LAWRENCE E. JOHNSON, a citizen of the United States of America, and a resident of Winthrop, in the county of Suffolk and State of Massachusetts, have invented certain new and useful Improvements in Sole-Leather-Cutting Machines, of which the following is a specification.

10 This invention relates to leather cutting machines and particularly to machines in this class adapted for cutting soles, the special object of the invention being to provide a simple and inexpensive machine which 15 may be used in a shoe repair shop for cutting out the half and whole soles used in repair work.

The invention consists primarily in mechanism for feeding the material and a 20 reciprocating knife in the path of movement of the material, said knife in addition to its reciprocatory movement having a vibratory movement first in the direction of feed and then in the opposite direction.

25 The invention further consists in certain novel features of construction and arrangement of parts which will be fully understood by reference to the description of the drawings and to the claims hereinafter given.

30 Of the drawings: Figure 1 represents an elevation of a machine embodying the features of the present invention. Fig. 2 represents an end view of the same. Fig. 3 represents a vertical section of the same looking toward the left of Fig. 2, the cutting plane being on line 3—3 of Fig. 1. Fig. 4 represents a similar section looking in the opposite direction, the cutting plane being on 35 line 3—3 on Fig. 1. Fig. 5 represents a vertical section, showing the cutting knife and the feed rolls, and Fig. 6 represents a left end elevation of the same, the supports for the channeling knife being shown in section.

45 Similar characters designate like parts throughout the several figures of the drawings.

50 In the drawings, 10 is the frame of the machine having mounted therein two parallel revoluble shafts 11 and 12. The shaft 11 is rotated by a crank 13 and has secured thereto and revoluble therewith the gear 14 meshing with the gear 15 secured to one end

of the shaft 12. It is obvious that when 55 the crank 13 is operated the shafts 11 and 12 will be rotated in opposite directions. The opposite ends of the shafts 11 and 12 have secured thereto the feed rolls 16 and 17 by which the material to be cut is fed. The 60 shaft 11 has mounted thereon and movable endwise thereof the guide member 18 having a forked lower end straddling a rib 19 formed upon the frame 10 to which it is clamped in adjusted position by means of 65 the clamp member 20.

In order to adjust the feed rolls 16—17 relative to each other for varying thicknesses of material the shaft 12 is mounted in eccentric bearings 21 mounted in the 70 frame 10 and each of which is provided with a depression into which extends a lug 22 formed upon the end of a yoke 23, having a handle 24 formed integral therewith by which said yoke may be moved to cause 75 said bearings 21 to be rotated about their axes and the axes of the shafts 11 and 12 moved toward or from each other as the case may be. The handle has secured thereto a slotted sector 25 through the slot of 80 which extends a clamp screw 26 threaded to an ear 27 extending upwardly from the frame 10, this clamp screw 27 being adapted to lock the yoke 23 and bearings 21 in their adjusted positions. Against the face 85 of the feed rolls 16—17 and secured to the shafts 11—12 are two eccentrics 28—29, preferably extending from said shafts in opposite direction as indicated in Fig. 5 of the drawings. The eccentric 29 is positioned 90 in a circular opening in the upper end of a cutting knife 30, the lower end of which is provided with an elongated slot 31 in which is positioned the eccentric 28. As the two eccentrics 28 and 29 rotate in opposite directions the knife 30 will be given a vibratory movement in the path of feed. As the eccentric 29 rotates the knife will be given a reciprocatory movement perpendicular to the material being fed.

95 The combined reciprocatory and vibratory movements of the knife 30 cause it first to move with the material being fed but at a slower speed and then to move against the material being fed. The principal work of the knife is accomplished 100 during this last half of the cycle when the cutting edge thereof is moving downwardly

- into the work. A reduced end 32 of the shaft 12 has mounted thereon a channeling knife 33, the upper end of which is provided with a slot 34 through which extends 5 the pin 35 extending outwardly from the lug 36 on the frame 10.
- The pin 36 has a washer 37 and a nut 38 thereon and the reduced end 32 is also provided with a washer 39 and a nut 40, these 10 nuts 38 and 40 serving to position the channeling knife 33. As the material is fed by the rolls 16-17 against the cutting edge of the knife 30 the knife 33 will cut a channel into the work.
- 15 The machine is particularly adapted for use in a repair shop, where, as a rule, unskilled labor is employed, making it particularly desirable that the machines used shall be extremely simple in construction 20 and free from liability to get out of order.
- When straight strips of leather or other material are to be cut, the gage 18 is adjusted and then used as a guide for the edge of the material. When this work is being done 25 the channeling knife is removed. When soles or half soles are being cut the guide 18 is not used, but, with a pattern as a guide, the soles are trimmed to the desired shape and the channel cut therein at the same time.
- 30 The teeth of the gears 14-15 are so constructed as to provide for the adjustment of the shaft 12 relative to the shaft 11 without moving said gears out of mesh with each other. The knife 33 is prevented from being 35 displaced upon the shafts 11-12 by the washer 39 and nut 40 on the shaft 12 and the washer 41 and nut 42 on the shaft 11.
- It is believed that the operation and many 40 advantages of this invention will be fully understood from the foregoing description.
- Having thus described my invention, I claim:
1. In a device of the class described, the combination of two parallel shafts revoluble 45 in opposite directions; a cutting knife; and means on said shafts for imparting a combined reciprocatory and vibratory movement to said knife.
  2. In a device of the class described, the combination of two feed rolls; a knife having 50 a cutting edge perpendicular to the axes of said rolls; and means revoluble with said feed rolls for imparting to said knife a combined simultaneously reciprocatory and vibratory movement in the same plane.
  3. In a device of the class described, the combination of two feed rolls; a knife having 55 a cutting edge perpendicular to the axes of said rolls; and means operable with said feed rolls for simultaneously reciprocating said knife and simultaneously moving it first in the direction of feed and then in the opposite direction.
  4. In a device of the class described, the combination of two feed rolls; a cutting 60

knife having an opening therethrough at one end; and an eccentric in said opening revoluble with one of said feed rolls.

5. In a device of the class described, the combination of two feed rolls; a cutting 70 knife having openings therethrough at opposite ends; and eccentrics in said openings revoluble with said feed rolls.

6. In a device of the class described, the combination of two feed rolls; a cutting 75 knife having openings therethrough at opposite ends; and eccentrics in said openings revoluble with said feed rolls, one of said openings being elongated to permit end movement of said knife relative to the eccentric positioned therein.

7. In a device of the class described, the combination of a cutting knife; a guide therefor at one end perpendicular to a side face of said knife; and means coacting with 85 the opposite end for simultaneously imparting thereto combined reciprocatory and vibratory movement in the same plane.

8. In a device of the class described, the combination of a cutting knife; a guide 90 therefor at one end perpendicular to a side face of said knife; and means coacting with the opposite end for imparting thereto a reciprocatory movement perpendicular to said guide.

9. In a device of the class described, the combination of a cutting knife; a guide therefor at one end perpendicular to a side face of said knife; and means coacting with 100 the opposite end for imparting thereto a vibratory movement with said guide as a pivot.

10. In a device of the class described, the combination of a cutting knife; and means 105 coacting with opposite ends thereof for simultaneously imparting thereto a combined reciprocatory and vibratory movement in the same plane.

11. In a device of the class described, the combination of a cutting knife; and means 110 for imparting independent movements to the opposite ends thereof.

12. In a device of the class described, the combination of a cutting knife; means for imparting independent movements to the opposite ends thereof; and means for feeding material against the cutting edge of said knife during the movement thereof.

13. In a device of the class described, the combination of two revoluble parallel shafts; feed rolls mounted on the ends thereof and revoluble therewith; eccentrics on the ends of said shafts; a cutting knife operable by said eccentrics; and means for adjusting said feed rolls relative to each other.

14. In a device of the class described, the combination of two revoluble parallel shafts; feed rolls mounted on the ends thereof and revoluble therewith; eccentrics on the ends of said shafts; a cutting knife operable by said 130

eccentrics; eccentric bearings for one of said shafts; and means for adjusting the position of said eccentric bearings to vary the positions of said feed rolls relative to each other.

5 15. In a device of the class described, the combination of two revoluble parallel shafts; feed rolls mounted on the ends thereof and revoluble therewith; eccentrics on the ends of said shafts; a cutting knife operable by 10 said eccentrics; eccentric bearings for one of said shafts; an adjustable yoke on said shaft provided at opposite ends with means for engaging said bearings; and means for locking said yoke in adjusted position.

15 16. In a device of the class described, the combination of a feed roll; a reciprocating knife in the path of feed; and a stationary channeling knife in said path.

17. In a device of the class described, the combination of work feeding mechanism; a 20 reciprocating knife in the path of feed; and a stationary channeling knife in said path.

18. In a device of the class described, the combination of a revoluble feed roll; a shaft 25 on which said roll is mounted; a reciprocating cutting knife in the path of feed; and a non-revoluble gage movable endwise of said shaft and adapted to be secured in adjusted position.

Signed by me at Boston, Mass., this 3rd 30 day of April, 1914.

LAWRENCE E. JOHNSON.
